UNITED STATES PATENT OFFICE

103,834

DESIGN FOR A FAN HOUSING

Howard H. Schott, Rochester, N. Y., assignor to
Robeson-Rochester Corporation, Rochester,
N. Y., a corporation of New York

Application February 3, 1937, Serial No. 67,425

Term of patent 7 years

To all whom it may concern:

Be it known that I, Howard H. Schott, a citizen of the United States, residing at Rochester, in the county of Monroe and State of New York, have invented a new, original, and ornamental Design for a Fan Housing, of which the following is a specification, reference being had to the accompanying drawings, forming part thereof.

Fig. 1 is a front elevation of a fan housing showing my new design;

Fig. 2 is a side elevation of the same;
Fig. 3 is a top plan view, and

Fig. 4 is a rear elevation.

I claim:

The ornamental design for a fan housing, substantially as shown.

HOWARD H. SCHOTT.
